E. H. WOLFF,
STOVEPIPE FASTENER,
APPLICATION FILED AUG. 11, 1920.

1,391,646.

Patented Sept. 20, 1921.

UNITED STATES PATENT OFFICE.

EDWIN H. WOLFF, OF EL DORADO, KANSAS, ASSIGNOR OF ONE-HALF TO SANK CLARK,
OF KINGSVILLE, KANSAS.

STOVEPIPE-FASTENER.

1,391,646.

Specification of Letters Patent. Patented Sept. 20, 1921.

Application filed August 11, 1920. Serial No. 402,770.

To all whom it may concern:

Be it known that I, EDWIN H. WOLFF, a citizen of the United States, residing at El Dorado, in the county of Butler and 5 State of Kansas, have invented certain new and useful Improvements in Stovepipe Fasteners; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this speci- 15 fication.

This invention relates to stove pipe fasteners, and particularly to means for securing the end of a stove pipe within the flue or chimney.

20 The invention contemplates the provision of means whereby the pipe may be conveniently introduced into the flue opening and fastened against accidental displacement.

25 In the drawings:

Figure 1 is a perspective view of the end of a pipe to which my invention is applied, the securing device being shown in the non-functional position.

30 Fig. 2 is a similar view showing the securing device in functional position.

Fig. 3 is a sectional view through a flue and pipe showing the fastening device in its securing position.

35 In carrying out the invention I provide a stove pipe section 1, near one end of which the cuts are made, as at 2 and 3, so that the portions of the section opposite the cuts constitute webs or strips 4 and 5, which 40 may be in-bent to provide bearings for a bolt 6. The portions 7 and 8 of the webs have alining openings for the bolt 6, as indicated in Fig. 1. There is a rigid collar 9 on the bolt 6 intermediate its ends so as to 45 constitute a stop, the stop being so positioned on the bolt 6 as to provide a short portion 10 and a long portion 11. Therefore, when the collar 9 rests upon the bearing portion 8, the end of the bolt 11 pro- 50 jects beyond the edge or perimeter of the pipe, but when the collar rests upon the bearing 7 the entire bolt will be within the

circumference of the pipe. Therefore when it is desired to apply the end of the pipe to the flue or chimney 12, the pipe will be 55 turned so that the bolt 6 will be in the position shown in Fig. 1, and after the pipe has entered the flue opening it will be turned so that the bolt may assume the position shown in Fig. 2, whereupon the end 11 of 60 the bolt 6 will overlap the lower edge 13 of the flue opening 14 and thereby prevent the accidental removal of the pipe, since the bolt end 11 will constitute a lock for the pipe. 65

If it is desired to subsequently remove the pipe from the flue opening, this can be accomplished by turning the pipe back to the position shown in Fig. 1, causing the bolt 6 to again move within the perimeter of 70 the pipe 1, whereby the pipe may be removed.

It will, therefore, be seen that an efficient and durable fastening means for stove pipes is provided. 75

What I claim and desire to secure by Letters-Patent is:

1. A stove pipe having inbent webs at one end, and a bolt mounted and slidable in the webs and movable in one direction 80 to extend beyond the perimeter of the pipe and movable in the opposite direction to a position within the perimeter of the pipe.

2. A stove pipe having bearings at one end, and a retaining bolt slidable in the 85 bearings, normally within the perimeter of the pipe but projectable beyond the same to abut against the inner face of a flue wall to hold the pipe in the flue opening.

3. A stove pipe, the wall of which is 90 oppositely cut near one end of the pipe to provide webs, the webs being bent inwardly toward one another to provide bearings, a bolt slidably mounted in the bearings, and a stop collar on the bolt to provide a long 95 portion and a short portion whereby the bolt may normally be confined within the perimeter of the pipe when the collar rests against one bearing but projects beyond the perimeter of the pipe when the collar 100 rests against the other bearing.

4. A stove pipe cut near one end to provide diametrically opposite, inbent, web portions having alining openings, a bolt

slidably mounted in the openings, and a collar on one side of the transverse center of the bolt to provide a long portion and a short portion, the length of the bolt being substantially equal to the diameter of the pipe whereby when the collar rests against one web, the bolt will be confined within

the perimeter of the pipe and when the collar rests against the other web, one end of the bolt will project beyond the perimeter of the pipe.

In testimony whereof I affix my signature.

EDWIN H. WOLFF.
